UNITED STATES PATENT OFFICE.

LEWIS PRESTON MALIN, OF LONG BEACH, CALIFORNIA.

WOOD-BENDING MACHINE.

Application filed September 20, 1921. Serial No. 502,009.

To all whom it may concern:

Be it known that I, LEWIS P. MALIN, a citizen of the United States, residing at Long Beach, in the county of Los Angeles 5 and State of California, have invented a new and useful Wood-Bending Machine, of which the following is a specification.

This invention has reference to the manufacture of extension tables and is particularly 10 designed for bending the half circle rims that constitute parts of such tables, and primarily my said invention has for its object to provide a machine for the purpose stated of a relatively simple and economical 15 construction, that comprises first, an improved means for feeding the glued wooden core or material to a steel framing or former and for turning the said framing as the said wooden core or material is being bent 20 thereon, and further means for holding the said wooden core, when bent to a rim shape, in a clamped condition.

In its more complete nature, my invention includes an improved means for first 25 tightly bending the core and veneer around the forming frame and devices for securing the said means whereby the said bent wooden core or rim is retained in its clamped 30 position, during the setting of such rim to its bent shape.

In its subordinate features, my invention embodies certain details of construction and novel combination of parts, all of which will 35 be fully set out in the following description, specifically pointed out in the appended claims and illustrated in the accompanying drawings, in which:

Figure 1 is a front elevation of my wood bending machine, the combined bending and 40 clamping band and the forming or shaping frame mechanism being at a position ready for receiving the wooden core and veneer that is to be bent into shape.

Figure 2 is an end elevation of the base 45 and upright framing, the bending mechanism and its vertically shiftable supporting frame being omitted, the power transmission and bending member guide roller being shown in operative relation.

Figure 3 is a front elevation of the forming frame and the cooperating means for 50 first bending the wooden core to a rim shape and for securing it onto the forming frame when it is bent.

Figure 4 is a detail cross section of the 55 rim of the forming frame.

Figure 5 is an enlarged side elevation, parts being in section of the metal devices that constitute a part of the forming frame and which are especially adapted for gripping the infed end of the wooden core or body.

Figure 6 is a detail view of the hook device on the outer end of the bending band 60 hereinafter referred to.

Figure 7 is a detail side view of one of the steel stud bolts attached to the main drive wheel to which the forming frame is clamped.

Figure 8 is a detail view of the cam lever 70 with which the hook on the bending band connects and which secures the said bending band around the core after it has been bent over the forming frame.

In the practical development of my invention, with the parts thereof detailed as shown in the drawings, 1 designates a base frame or table that includes front and back uprights or legs 10-10, in practice about two feet high, and connected by cross beams 80 11 and 12 and upon which is supported a table top 13.

2-2 designate two upright posts bolted at their lower ends to the cross beams 12 and they pass through openings in the table 85 top 13, as shown.

The posts 2-2 are vertically grooved as at 20-20 to constitute guides for the side flanges or tennons 30 of a supplemental frame which includes opposite uprights 3-3 90 on which the tennons 30 are formed and which are connected at their top and bottom by cross members 31-31 and a midway horizontal beam 32 which latter constitutes the supporting element that sustains 95 the forming frame devices over which the wood core is bent, as will be presently fully explained.

The supplemental frame, hereinafter termed "the lifting frame," is vertically 100 movable along the posts 2-2 for a quick adjustment of the different sizes of the steel forming frames, and to that end one of the uprights 3 has a series of vertically elongated apertures 33 for receiving a lock pin 34 that fits through one of the side posts 2 and is adapted for engaging with a desired one of the apertures 33, the vertical elongation of the said apertures permitting sufficient play to allow the forming frame 105 to rest on a flanged roller 4 that is journaled in the table top with its upper edge 110

40 flush with the said table top, as is clearly shown in Figure 2.

The upright 3 that has the elongated apertures 33 is also provided with stud pins 34^a for cooperating with a lifting lever 5 that is fulcrumed on the front face of the adjacent side posts (see Figure 1) it being understood that when the lever is positioned, as in Figure 1, by removing the lock pin 4, the vertically movable lifter frame can be adjusted, as desired.

As before noted, the midway cross beam 32 of the lifter frame constitutes the supporting element upon which the wood shaping or forming mechanism is sustained, and at this point it should be mentioned the said mechanism includes a forming or shaping means adapted for being detachably mounted, in relation to the permanently mounted power transmission mechanism, the latter, and the forming rim, having interengaging means whereby the said transmission mechanism is adapted for sustaining forming or shaping frames of different sizes, as will presently more fully appear.

Referring now more particularly to Figures 1 and 2 of the drawings, it will be observed a crank shaft 6 is journaled in a suitable bearing 60 on the bottom cross member 32 of the lifter frame whose outer end carries a cog. pinion 7. The pinion 7 meshes with a main cog transmission wheel 14 that is fixedly mounted on the reduced or flanged end 80 of a shaft 8 that is journaled in a sleeve bearing 81 on the cross member 32.

The said main or transmission wheel 14 has a series of stud bolts 15 projected from its outer face, each of which has an annularly grooved head 15^a that latches the steel metal forming frame onto the wheel 14 to turn therewith, as presently further explained.

The forming mechanism comprises a steel frame that is composed of a semi-circular member 16, T shaped in cross section, and a shaping rim 16^a which is riveted to the member 16, as shown in detail in Figure 4, a T shaped cross member 18, the opposite ends of which are riveted to the opposite ends of the semi-circular member 16 and a central brace member 19 whose outer end is riveted to the member 16 and whose inner end is secured to the cross member 18, as is clearly shown in Figures 1 and 2, by reference to which it will also be observed a pair of angled brackets 21 are riveted to the under side of the cross member 18, centrally thereon, which brackets provide a central bearing for pivotally and loosely mounting the forming frame on the outer projected end of the shaft 8 that carries the main cog wheel 14.

Bifurcated lugs 22 are riveted to the opposite ends of the cross member 18 and brace member 19 which constitute the locking ele-

ment for securing the forming frame onto the main cog wheel 14 to rotate therewith in the direction indicated, by the arrow on Figure 1, the said bifurcated lugs engaging the annular heads of the stud projected from the said wheel, as shown.

The means for connecting the forming frame to the wheel are such that one frame may be readily removed from the wheel 14 to be replaced by a forming frame of another size, as desired, it being understood the forming frames are not fixedly attached to the wheel 14 but are merely mounted thereon to turn therewith, as stated.

At one side of the main table is hingedly connected a long supplemental table or platform 23, the outer end of which is supported by a leg 23^a, when the said supplemental table is swung down to the operative position shown in Figure 1. By hinging the supplemental table portion, as stated and shown, it may be readily swung up out of way when the machine is not in use and against the adjacent upright post 2; as shown in dotted lines in Figure 1.

24 designates a strap iron band, which is hereinafter termed the bending and clamping element, one end of which is adjustably secured to one edge of the forming wheel, the adjustment thereof providing for lengthening or shortening the band for the different diameters or sizes of the forming frame. The band 24, when at the extended position, lies flatwise on the table 23 and its outer end is provided with a malleable iron eye hook 24^a (see Figures 1 and 6) that is engaged by a cam lever 51 that is located at the edge of the forming frame opposite the edge to which the band is adjustably joined.

At the edge of the forming frame, where the infed end of the core to be bent is received, is an attached clamping means for firmly gripping the said end of the core and securing it as the remainder is bent over the forming frame and clamped at the other end thereof in the manner best shown in Figure 3. The aforesaid mentioned clamping means comprises a bracket iron 35 that is held on the under side of the cross member 18 of the forming frame by a bolt 36 which passes through the flange of the said member 18, and through a longitudinal slot 37 in the iron 35, as is best shown in Figure 5, which illustrates a simple and effective means for adjusting the iron 35 radially with respect to the fulcrum of the forming frame, whereby to determine the length of the bending band to suit the special sizes of the forming frame used.

The adjusting means stated consists of an angle bracket 38 which is attached to the underside of the cross member 18, and an adjusting screw 39 that is mounted in the bracket 38 and engages with a threaded

aperture 35^a in the angled end 35^b of the iron 35, it being apparent that by the screw connection stated the angle iron 35 can be drawn in or extended along the corresponding edge of the forming frame, as conditions may make necessary.

The iron 35 includes a segmental bearing 35^c whose outer face has ratchet-like teeth 35^d for cooperating with a core end 10 gripping member with which the inner end of the bending band is fixedly joined, as is clearly shown on the drawing.

The gripping member consists of a segmental shaped iron 41 that is provided along 15 its under face with ratchet-like teeth 43 for interengaging the ratchet teeth 35^d on the iron 35.

The iron 41 is of sufficient length to normally project beyond the edge of the forming frame over which the innermost end 20 of the wooden core is fed when placed in position for being bent to form a table frame piece, and the outer end of the said iron 41 has a transverse row of sharp teeth 25 41^a, in practice one-eighth of an inch long, which are forced into the said core ends as the process of bending the core begins.

To provide attachment of the iron 41 along the iron 35 the inner end of the said 30 iron 41 has an elongated slot 41^b for the passage of the screw shank of a bolt 42 that is attached to the iron 35 and which receives a clamping nut 42^a, as shown.

The forward end of the bending band 35 extends over and is riveted to the iron 41, as shown.

Operation.

The parts being constructed in the manner so far described and shown, and assuming the forming frame and the bending band to be in the position shown in Figure 1, the parts are now ready for receiving the wooden core to be bent, which is laid flatwise onto the bending band with its forward 40 end projected between the now bottom edge of the forming frame and the gripping element attached to such end of the frame, as indicated on Figure 1.

Power being now applied to the shaft 8 to turn the main wheel in the direction of the arrow α , the forming frame rotates with the said wheel and carries the bending band with the wooden core thereon with it, under the continuously changing bottom part 45 of the forming rim of the frame, until the other edge of the said frame reaches its bottom position, that is, when the full length of the band, with the wooden core, 50 has been bent over the forming frame, as shown in Figure 3.

When the core and the band are fully bent onto the forming frame, as stated, a cam lever 51 pivoted to that edge of the 55 forming frame opposite the core receiving

edge, is drawn through the slotted hook at the end of the band and bent back to the position shown in full lines on Figure 3, and thereby secures the band with the core in the bent over position, the band now 70 holding the said core until it is set to its bent shape, after which, by simply turning the cam lever back to disengaging the hook 24^a on the band, the latter can be conveniently drawn back to its flat position, it being guided by the flange wheel 4, as it is thus drawn back and the wheel 8 with the forming frame reversely rotated back to the position shown in Figure 1.

While I have described my mechanism as adapted for being worked with hand crank power, it is obvious that the power may be a motor controlled transmission with the motor mounted on the lifter frame to move up and down with it, the said motor 80 being switch-controlled, as is usual in power generating mechanism of the kind stated.

While the details of construction shown and described disclose a practical development of my invention, it is to be understood 90 that the said details may be varied and modified to suit the desired conditions for which my invention may be used, without departing from my invention as defined in the appended claims.

From the foregoing description, taken in connection with the accompanying drawing, the complete construction, the method of operation and the advantages of my wood bending mechanism will be readily 95 apparent to those familiar with the manufacture of end strips for extension tables.

What I claim is:

1. In a wood bending machine of the character described, a main frame which includes a table, a pair of rigid uprights that extend through the table, a lifting frame vertically movable along the uprights, and means cooperating with the lifting frame for holding the said lifting frame to different vertical adjustments relatively to the table, a forming frame having a semi-circular rim, said forming frame being journaled on the lifting frame with its rim face opposing the table, a bending band adapted to lie flatwise on the table and to pass between the table and the rim of the forming frame, means on the forward end of the semi-circular rim for clamping the forward end of the bending band to cause it to travel around with the rim of the forming frame, the said band and the forming frame rim constituting the seat for receiving the forward end of the wooden core to be bent, the said means for clamping the band comprising a segment on the forming frame, a segment on the band for connecting with the other segment, and means for holding the two segments interlocked.

2. In a machine for bending half circular 130

frames for extension tables, a table, a supporting frame that projects vertically from the table, a guide roller on the table top, a forming frame having a semi-circular rim, the said rim being journalled on the vertical supporting frame with its rim face opposing the guide roller, a bending band adapted to rest flatwise on the table and to pass between the guide roller and the rim of the forming frame, one end of the said band being fast to one edge of the forming frame and which constitutes with the said frame a seat for receiving the forward end of the wooden body or core to be bent, a clamp device on the aforesaid edge of the forming frame adapted to grip the said wooden body and pull it with the board between the frame rim and the table guide and around the forming frame rim as the said frame is rotated, means on the other edge of the forming frame for clamping the outer end of the band whereby to hold it and the wooden core to their bent shape about the forming frame rim, the said clamping means comprising a segment interlockably engaging the edge of the forming rim and devices for effecting longitudinal adjustment of the said segment.

3. In a machine for bending half circular frames for extension tables, a table, a supporting frame that projects vertically from the table, a guide roller on the table top, a forming frame having a semi-circular rim, the said rim being journalled on the vertical supporting frame with its rim face opposing the guide roller, a bending band adapted to rest flatwise on the table and to pass between the guide roller and the rim of the forming frame, one end of the said band being fast to one edge of the forming frame and which constitutes with the said frame a seat for receiving the forward end of the wooden body or core to be bent, a clamp device on the aforesaid edge of the forming frame adapted to grip the said wooden body and pull it with the board between the frame rim and the table guide and around the forming frame rim as the said frame is rotated, means on the other edge of the forming frame for clamping the outer end of the band whereby to hold it and the wooden core to their bent shape about the forming frame rim, the said clamping means comprising a segment interlockably engaging the edge of the forming rim, devices for effecting longitudinal adjustment of the said segment, the inner end of the bending band passing over and fixedly connected to the inner end of the said segment.

4. In a machine for the purpose stated, the combination with a table, a supporting frame that extends vertically from the table

and a supplemental frame cooperative with the main vertical frame and vertically adjustable relatively to the said main vertical frame; of a forming frame rotatably mounted upon and movable vertically with the supplemental frame, said forming frame including a semi-circular forming frame, a bending band adapted to lie flatwise on the table and to receive the wooden core or body flatwise thereon, with one end thereof adjacent one edge of the forming frame rim, means for securing the forward end of the band and for clamping the corresponding end of the core to the forming frame, means for effecting the rotation of the forming frame, whereby to pull the bending band and the wooden core between the forming frame rim and the table and around the said rim, further means for holding the band and the core in their bent shape onto the said rim, means for effecting rotation to the forming frame comprising a master gear, power transmission joined therewith and operative connections that join the forming frame and the master gear, the said operative connections comprising studs projected from the outer face of the master gear and locking lugs on the forming frame for interlockably and removably engaging the said lugs whereby to provide for mounting forming frames of different diameters onto the said master gear.

5. In a wood bending machine of the character described, the combination with a table, a main supporting frame, a supplemental supporting frame supported by and having vertical adjustment along the main supporting frame, a power shaft journalled transversely on the said supplemental supporting frame, a forming frame axially fulcrumed on the said power shaft and having radial arms connecting with a semi-circular forming rim, a bending band, the said band and the forward end of the forming frame having coengaging clamp devices for attaching the band to the rim to bend the wooden core around the said rim, the rear end of the band and the rear end of the rim having lever controlled means for clamping the band and the wooden core to their bent around position, means for effecting rotation of the forming frame, the said means comprising a master gear on the power shaft, the said means including operative connections that interlockably join the radial members of the forming frame, and the master wheel to thereby cause the forming frame to turn with the said master wheel, and other means for imparting motion to the power shaft.

LEWIS PRESTON MALIN.
